(57) **CLAIM**

The ornamental design for a finger ring, as shown and described.

DESCRIPTION

1. Finger ring
- 1.1 : Perspective view 1
- 1.2 : Perspective view 2
- 1.3 : Front
- 1.4 : Back
- 1.5 : Bottom
- 1.6 : Right

The characteristic features of the design reside in the shapes as shown in the reproductions; the rear view is omitted because it is an identical image of the front view; the left view is omitted because it is an identical image of the right view.

1 Claim, 6 Drawing Sheets
